UNITED STATES PATENT OFFICE.

JOHN JUHASZ, OF NEW YORK, N. Y., ASSIGNOR TO JUHASZ CARBURETER CORPORATION, OF NEW YORK, N. Y., A CORPORATION OF NEW YORK.

CARBURETOR.

Application filed May 9, 1923. Serial No. 637,743.

The present invention relates to improvements in carburetors, and has for its main object to provide a nozzle which automatically produces a proper fuel mixture, without the use of moving parts, under all conditions of operation of the engine.

In plain tube carburetors the flow of fuel from the nozzle increases under suction faster than the flow of air, giving a mixture which grows richer and richer, a mixture containing a higher percentage of fuel at high vacuum than at low. In order to overcome this trouble it has been proposed heretofore to bleed air into the nozzle, the arrangement in several well known carburetors being such that a series of air vent or compensating holes are progressively uncovered as the throttle is gradually opened and the suction in the nozzle increases, the mixture being thus diluted. While these carburetors have been found to be efficient at high speed, they produce a too rich mixture at lower speeds.

One of the objects of the present invention is to overcome this defect.

Two of the many possible embodiments of the present invention are illustrated in the accompanying drawings, in which:

Figure 1 is a sectional elevation of a portion of a carburetor, showing the improved nozzle; Fig. 2 is a central vertical section taken through the nozzle, on a larger scale; and Fig. 3 is a similar section of a modified form of the improved nozzle.

In Fig. 1 of the drawings, a multi-nozzle carburetor is illustrated, but attention is called to the fact that the improved nozzles herein described may be applied to single nozzle carburetors just as well.

Referring now first to Figs. 1 and 2 of the drawings, the numeral 10 indicates a carburetor casing, in the side of which is formed an opening 11, forming the air inlet to the carburetor chambers 12 and 13, which are in the present case in the form of Venturi passages. Into each of these passages projects a fuel nozzle 14, which communicates with a float chamber 15 of any suitable construction, the inlet openings of the nozzles being controlled, for instance, by needle valves 16, although this is not essential. Above the carbureting chambers is disposed a throttle 17, in the present case

a cylindrical throttle; for the well known purpose.

Each of the carburetor nozzles 14 comprises a tube 18, the bore 19 of which is divided into a plurality of sections of varying transverse cross sections. The transverse cross sections of these bore sections gradually decrease from the uppermost section to the lowermost, as clearly shown in Figs. 1 and 2 of the drawings. The lower end of the tube is provided with a flange 20, on which rests the flange 21 of a tube 22, which encloses the tube 18 and is spaced therefrom. The upper open end of the tube 22 is disposed a slight distance below the upper end of the tube 18, onto the latter being fitted a cap 23 which extends a substantial distance downwards over the tube 22, but is spaced from the latter. The lower open end of the cap is outside the suction area of the nozzle, air flowing into the space between the tube 22 and the said cap at substantially atmospheric pressure. This air flows into the space between the tube 18 and the tube 22, and from the latter space into the tube 18, as will be presently described.

The flanges 21 and 20 above-referred to are disposed in a bore 24 in the carburetor casing, a gasket 25 being interposed between the flange 21 and a shoulder 26 in the said bore, the elements being held in proper position by a screw plug 27, having an aperture 28 in constant communication with the float chamber 15. The size of the aperture 28 corresponds, preferably, to that of the lowermost bore section of the tube 18, with which it communicates.

The tube 18 is provided with a plurality of holes 29, one associated with each bore section, save with the lowermost bore section. Through these holes the tube 18 is adapted to communicate with the space between the latter and the tube 22, as will be herein-after pointed out.

Each of the bores 24 is closed by a screw plug 27', through which the screw-threaded stem of a needle valve 16 extends. When the plugs 27 and 27' are removed, each of the nozzles may be removed, as a unit, from the carburetor casing.

The operation of this device is as follows: When the engine is not running, and con-

sequently there is no vacuum in the carbureting chambers, the fuel rises in the tube 18 approximately to the dotted line shown in Fig. 2 of the drawings and, as this tube 5 communicates through the holes 29 with the space between the tube 18 and the tube 22, fuel rises to the same height in the said space. From this it appears that the inlet to the tube 18 is submerged a substantial 10 distance below the normal fuel level. When the engine is started and the throttle is gradually opened, obviously the suction in the tube 18 increases, thereby lowering the fuel level in the said tube and in the space 15 between the latter and the tube 22. The air bleed or compensating holes 29 are thus progressively uncovered. Since air passes into the space between the cap 23 and the tube 22 at atmospheric pressure and a vacuum 20 exists in the tube 18, this air rushes through the said holes into the tube 18 at substantially right angles to the flow of the fuel vapor therein, mixing with the latter and thereby diluting the mixture. The 25 higher the suction acting upon the tube 18, the lower will be the level of the fuel within the same, and therefore more of the compensating holes will be uncovered, permitting of a greater dilution of the mixture. 30 At higher speed the tube 18 is practically empty and all of the compensating holes are in action.

Tests, which have been made with the carburetor herein described, show that the 35 stepped cross-section of the tube 18 gives a material reduction in fuel consumption, and that this reduction in fuel consumption may result from improved atomization of the fuel. It appears that the stepped cross-section 40 gives space for the increased volume due to the mixture of fuel with the air which is vented through the holes 29.

The modification illustrated in Fig. 3 of the drawings differs from the one above described in that, instead of the compensating holes 29, a longitudinal slot 30 is provided in the tube 18, said slot extending from the uppermost bore section of the tube to substantially the lower end of the next to the 45 last bore section thereof. This slot provides a more gradual and even inflow of air into the tube 18 than the holes 29 above referred to. Otherwise the construction and

operation of the elements shown in Fig. 3 of the drawings are the same as of those described in Figs. 1 and 2 of the drawings.

What I claim is:

1. A carburetor nozzle comprising a suction-controlled tube the bore of which gradually decreases in transverse cross section from its upper end to its lower end, a fuel connection leading to the lower end of said tube, a second tube enclosing said first-mentioned tube and spaced therefrom, and a cap fixed to the upper end of said first-mentioned tube extending over the said second-mentioned tube and spaced from the latter, said first-mentioned tube being provided with openings between said fuel connection and its upper end and being normally sealed by the fuel at low speeds and admitting air into said first-mentioned tube under high speeds.

2. A carburetor nozzle comprising a suction-controlled tube provided with a bore having a stepped cross-section, a fuel connection leading to the lower end of said tube, said tube being provided with openings at different levels between said fuel connection at its upper end, and means for supplying air to the said openings and at the same time preventing leakage of fuel therethrough, said openings being normally sealed by the fuel at low speeds and admitting air into said tube in succession at high speeds.

3. A carburetor nozzle comprising a suction-controlled tube the bore of which gradually decreases in transverse cross section from its upper end to its lower end, a fuel connection leading to the lower end of said tube, a second tube enclosing said first-mentioned tube and spaced therefrom, and a cap fixed to the upper end of said first-mentioned tube extending over the said second-mentioned tube and spaced from the latter, said first-mentioned tube being provided with an opening between said fuel connection and its upper end normally sealed by the fuel at low speeds and admitting air into said first-mentioned tube under high speeds.

Signed at New York, in the county of New York, and State of New York, this 8th day of May, A. D. 1923.

JOHN JUHASZ.
